(57) **CLAIM**

The ornamental design for a pants combined with pouch waistband, as shown and described.

DESCRIPTION

FIG. 1 is a front perspective view of a pants combined with pouch waistband;

FIG. 2 is a front elevation view of FIG. 1;

FIG. 3 is a rear elevation view of FIG. 1;

FIG. 4 is a left side elevation view of FIG. 1, the right side elevation view being a mirror image thereof;

FIG. 5 is a top plan view of FIG. 1;

FIG. 6 is a bottom plan view of FIG. 1; and,

FIG. 7 is a perspective view of the pants combined with pouch waistband, with the pouches shown in intended use. The equal-length broken lines depict environmental subject matter that forms no part of the claimed design, while the unequal-length broken lines represent the bounds of the claimed design.
